CLAIM

The ornamental design for a protective glove for pumping gasoline, as shown and described.

DESCRIPTION

FIG. 1 is an exploded perspective view of the protective glove for pumping gasoline showing my new design;

FIG. 2 is a front elevational view of the protective glove for pumping gasoline shown in FIG. 1; and, FIG. 3 is a side elevational view of the opposite of the protective glove for pumping gasoline from that shown in FIG. 1.

FIG. 1

FIG. 2

FIG. 3
